UNITED STATES PATENT OFFICE.

HARVEY F. GASKILL, OF LOCKPORT, NEW YORK; MARY E. GASKILL
EXECUTRIX OF SAID GASKILL, DECEASED.

ROTARY DOUBLE-PISTON LIQUID-METER.

SPECIFICATION forming part of Letters Patent No. 421,489, dated February 18, 1890.

Application filed September 3, 1888. Serial No. 284,456. (No model.)

To all whom it may concern:

Be it known that I, HARVEY F. GASKILL, of Lockport, New York, have invented certain new and useful Improvements in Liquid-Meters, of which the following is a specification.

My invention may be best understood from the subjoined description of the accompanying drawings, in which—

Figure 1 is a central sectional elevation on line C D of Fig. 3. Fig. 2 is a central sectional elevation on line A B of Fig. 3 at right angles to Fig. 1. Fig. 3 is a horizontal section on line E F of Fig. 2, but with cover *i* removed. Fig. 4 is a plan of the base-piece. Fig. 5 is a plan of the lower cylinder. Fig. 6 is a central sectional elevation of the lower cylinder. Fig. 7 is a plan of the plate which separates the two cylinders. Fig. 8 is a side view of said plate. Fig. 9 is a plan of the rotating piston. Fig. 10 is a central sectional elevation of the piston. Fig. 11 is a plan of the upper cylinder. Fig. 12 is a central sectional elevation of the upper cylinder.

The meter shown in the drawings consists, in its main parts, of a base, two cylinders, one above the other, mounted on the base and having water-passages in their peripheral sides, a rotating piston in each cylinder, a separating-plate between the cylinders, provided with cut-off flanges projecting into the cylinders to separate the inlet from the outlet, a cover-plate for the upper cylinder, a surrounding casing, and gearing and counting or registering mechanism.

The base-casting A (shown in plan in Fig. 4 and in section in Figs. 1 and 2) is provided with nozzles *x* *x'*, which may be threaded, as shown, for making connections. One of these *x'* contains the inlet-opening and the other *x* the outlet. The body of the casting is hollow, as shown, and the inlet, which occupies the center and one side of the interior chamber, is divided by a web or membrane B from the outlet.

C is the lower cylinder. It is circular in form with a circular interior chamber D. Water enters this chamber at *c'* and leaves it through the passage *g* and opening *k'*, Fig. 5. The upper cylinder F is of similar construc-

tion, with a chamber G, an inlet *d'*, and outlet *h* *k*, Fig. 11.

The pistons H are preferably of the form shown in Figs. 9 and 10, with openings *a*, and may be made of rubber or other suitable material. They are somewhat smaller in diameter than the chambers D and G, and are arranged in the chambers so as to be in contact with their walls at one side.

c is a shaft stepped at its lower end in the base-casting and extending up centrally through the chamber D and G. Upon that part of shaft *c* which is within the chambers a hollow shaft *b* is eccentrically secured, and upon this shaft *b* the pistons H are mounted. As a result of this arrangement the pistons, when in place, are concentric with shaft *b*, but eccentric to *c* and to the chambers, and are in contact with the walls of the chambers at one side, and as the pistons sweep around in the chambers they will revolve upon shaft *b* and roll upon the walls of the chambers like wheels, thereby greatly reducing friction. The inlet and outlet sides of the chambers are divided by T-shaped pieces *e* and *f*, one in each chamber, which extend from top to bottom of their respective chambers and have their heads against their respective pistons and their webs arranged to slide, like sliding doors, into spaces *a'* and *b'* in the dividing-walls which separate the inlet-passages *c'* and *d'* from the outlet-passages *g* and *h*. These pieces *e* and *f* are both connected to a plate *d* at opposite sides and on opposite surfaces thereof, and the plate is arranged between the two cylinders, so as to separate the chambers D and G from each other. As the pistons H travel around, the pieces *e* and *f* move in and out in unison and the plate *d* slides with them.

i is a covering-plate on the top of cylinder F.

y are bolts or screws which fasten the two cylinders to the base A.

p is a pinion on the upper end of shaft *c*.

s is a gear whose arbor is supported in a bridge *n*.

q is a gear meshing with pinion *p*, and *r* is a pinion on the same arbor as gear *q* and mesh-

ing with gear *s*. The object of this arrangement is to reduce the speed between shaft *c* and the counter mechanism.

m is the casing of the meter, secured to base *A* and inclosing the cylinders, &c.

u is a shaft mounted in a bearing in casing *m* and passing through a stuffing-box to prevent leakage.

At *t* shaft *u* is coupled to the arbor of gear *s*. When it is desired to open the meter, the coupling *t* parts, and the casing may be lifted without disturbing the gearing.

At *w* are lugs on casing *m*, for the support and attachment of the counting mechanism which is coupled to shaft *u*. I have not thought it necessary to show this mechanism, as its construction forms no part of my present invention.

In operation the water or other liquid to be measured enters at *x'*, and, following the course indicated by the arrows, passes up through openings *Z Z*, around the cylinders, and up through the central opening, through shaft *b*, and through the pistons at *a*, and fills casing *m*. Thence it passes through *d'* into chamber *G*, and, turning the piston therein, passes out at *h*, down through *k*, and out at *x*. It also passes through *c'* into chamber *D*, and, turning the piston therein, passes out through *g* and down through *k'* and out at *x*. Each piston is carried past its dead-point by the other piston, which at that moment will be at mid-stroke.

What I claim is—

1. The combination, substantially as set forth, of the two cylinders *C* and *F*, the pistons moving therein, the sliding separating-plate *d*, and abutment-pieces *e* and *f*.

2. A liquid-meter having two circular measuring-chambers having a common axis, cylindrical pistons revolving therein, an abutment for each piston, and a sliding plate separat-

ing the pistons and moving the abutments, the said pistons being always at opposite points of their strokes, substantially as set forth.

3. In combination with the casing provided with suitable inlets and outlets, two superimposed cylinders *C* and *F*, axially in line with each other, having openings *c' d'* in their walls communicating with the interior of the casing, and with openings *k* and *k'*, communicating with the discharge-outlet of the casing, pistons mounted eccentrically within the cylinders diametrically opposite each other, and a sliding plate provided with abutment-pieces *e* and *f*.

4. In combination with the casing provided with suitable separated inlet and outlet openings, stationary superimposed cylinders *C* and *F*, having hollow walls the spaces of which communicate with the inlet and outlet openings in the casing, the eccentrically-mounted rotatable pistons, and valves.

5. In combination with a suitable casing, stationary superimposed hollow-walled cylinders provided with inlet and discharge openings, rotating pistons mounted eccentrically within the cylinders and arranged diametrically opposite each other, and movable abutments against which the pistons act.

6. In combination with a suitable casing, superimposed hollow-walled cylinders provided with inlet and discharge openings, rotating pistons mounted eccentrically within the cylinders diametrically opposite each other, and provided with openings, a hollow shaft by which said pistons are carried, and a plate *d*, cut away at its middle and provided with abutments.

HARVEY F. GASKILL.
